UNITED STATES PATENT OFFICE.

SOL GREENBERG, OF CHICAGO, ILLINOIS.

DESIGN FOR A HAT OR SIMILAR ARTICLE.

52,112.

Specification for Design.

Patented June 18, 1918.

Application filed February 4, 1918. Serial No. 215,364. Term of patent 3½ years.

To all whom it may concern:

Be it known that I, SOL GREENBERG, a citizen of the United States, and residing in the city of Chicago, county of Cook, and State of Illinois, have invented a new, original, and ornamental Design for a Hat or Similar Article, of which the following is the specification, reference being had to the accompanying drawings, forming a part thereof.

In the drawings:

Fig. 2 is a view of the side opposite that shown in Fig. 1.

Fig. 3 is a rear view thereof.

Fig. 4 is a top view thereof.

I claim:

The ornamental design for a hat or similar article, as shown.

SOL GREENBERG.

Witnesses:

CHARLES W. HILLS, Jr.

FRED E. PAESLER.
